UNITED STATES PATENT OFFICE.

ROBERT E. HUMPHREYS, OF WHITING, INDIANA, AND WILLIAM M. BURTON, OF CHICAGO, ILLINOIS, ASSIGNORS TO THE STANDARD OIL COMPANY, OF CHICAGO, ILLINOIS, A CORPORATION OF INDIANA.

DISTILLATION OF PETROLEUM-OILS.

1,343,674.

Specification of Letters Patent. Patented June 15, 1920.

Application filed November 28, 1916. Serial No. 133,871.

To all whom it may concern:

Be it known that we, ROBERT E. HUMPHREYS and WILLIAM M. BURTON, citizens of the United States, residing at Whiting, in the county of Lake and State of Indiana, and Chicago, in the county of Cook and State of Illinois, respectively, have invented a new and useful Improvement in Distillation of Petroleum-Oils, of which the following is a specification.

Our invention relates to certain new and useful improvements in the art of distilling petroleum oil. We are particularly concerned with a distillation process in which relatively heavy petroleum hydrocarbons are treated under high temperatures and pressures for the purpose of effecting their conversion into relatively light hydrocarbons, the object of our invention being to secure the largest possible yield of light hydrocarbon of the desired character, at a minimum cost of treatment. The manner in which this object is accomplished by our invention will be fully understood from the following specification, taken in connection with the accompanying drawings, in which—

Figure 1 is a side elevation of a still and its connected apparatus arranged for carrying out our invention, the showing being largely diagrammatic; Fig. 2 is an enlarged horizontal sectional view through the diaphragm by which the stoker-controller is governed; Fig. 3 is an enlarged section through the stoker-control valve; Fig. 4 is an enlarged section through the cylinder of the stoker-control mechanism; and Fig. 5 is an enlarged section through the needle-valve by which the vapors of distillation are admitted to the final condenser.

Referring more particularly to the drawings, the numeral 10 designates a furnace structure, and the numeral 11 a mechanical or automatic stoker for firing the same. Above the furnace 10 there is mounted a still 12 to be heated thereby, which still may be of the form illustrated in the patent to Robert E. Humphreys (one of the present applicants), No. 1,122,003, or may be of any other convenient form. From the still a vapor-conduit 13 leads rearwardly and upwardly, and is surmounted by an air-condenser in the form of a radiator 14, all of the conduits of which are so arranged as to drain their condensate backwardly.

From the top of the radiator 14 a vapor-outlet pipe 15 is carried, this pipe feeding the final condenser 16, which will usually be mounted in a water-bath 17, as illustrated. The condensate from the condenser 16 drains into a receiving-drum 18, from which it may be drawn off continuously or intermittently through the gasolene main 19. The upper end of the receiving-drum 18 has tapped thereinto a pipe 20 which leads into the lower portion of the body of a Gay-Lussac tower 21, which may be filled with crushed quartz, coke, or other inert material forming a permeable bed. A gas-outlet pipe 22 is connected with the top of the Gay-Lussac tower and liquid inlet and outlet pipes 23, 24 are connected with the top and bottom of the tower, respectively.

Intermediate the length of the vapor-pipe 15 there is inserted a pressure-control valve 25, which is preferably of the construction illustrated in Fig. 5, having an exceedingly small valve aperture 26, the size of which may be accurately controlled by a needle 27. For the convenient manipulation of the said valve we prefer to provide the needle 27 with an extended rod-connection 28 through which the valve may be controlled from the ground level as by means of the hand-wheel 29, operating through 30 the miter gears 30.

Between the radiator 14 and pressure-control valve 25 the pipe 15 has tapped thereinto a pressure-conduit 31 which leads to the lower side of the diaphragm chamber 32 (Fig. 2). A flexible and imperforate diaphragm 33, mounted horizontally within the said chamber has attached to its center a rod 34 carrying a knife-edge 35, which bears against the lower face of a balance-beam 36, fulcrumed on a knife-edge 37, as shown in Fig. 2. The free end of the beam 36 carries suitable weights which may be arranged in the usual manner to secure accurate loading of the beam. Midway of its length the beam supports a stirrup 38, which through a suitable link-connection operates a piston-valve 39, vertically reciprocable within a cylindrical casing. A conduit 40 connects a port in this casing with the base of a cylinder 41, from which power is derived for operating the valve of the stoker-engine, as will later appear. The admission of fluid under pressure to the conduit 40, or the exhaust of fluid therethrough, 110

is effected by the movement of the valve 39, the latter being provided, for instance, with straight and angular passages 42, 43, respectively, arranged in the manner shown 5 in Fig. 3 and adapted according to the position of the valve to connect the conduit 40 with a fluid-pressure pipe 44 or with an exhaust pipe 45.

Within the cylinder 41 a piston 46 operates, the piston-rod thereof being connected, as illustrated diagrammatically in Fig. 1, with one end of a rocking-lever 47 journaled in suitable supports above the still. One end of the lever 47 is connected, as by 15 the chain 48, with a lever 49 which actuates the throttle-valve of a steam-engine 50, which is belted to drive the mechanical stoker 11. A second chain connection 51 from the lever 47 operates a damper 52, by 20 which the flow of air for combustion in the furnace 10 is controlled.

Method of operation.

In utilizing the apparatus above described 25 for the purpose of converting relatively high boiling-point petroleum hydrocarbons, such, for instance, as fuel-oil, gas-oil, or the like residues, into lighter hydrocarbons of the nature of gasoline, the procedure is 30 as follows:

The still 12 having been charged with a quantity of such heavy hydrocarbons, the furnace 10 is fired, and the automatic or mechanical stoker 11 is put into operation to 35 continuously supply to the furnace the normal amount of fuel. During the initial heating of the charge within the still 12, that is, up to the time when this charge reaches a temperature of 300° F. or there- 40 about, the needle-valve 27 is preferably kept wide open in order that any small quantities of low-boiling point liquids present in the charge, and more especially any water which may have become accidentally 45 admixed therewith, may be freely driven off. When the above-mentioned temperature has been reached the valve 27 may be closed and the heating continued until a pressure of 50 four atmospheres or upward, depending upon the specific character of the charge under treatment, is reached. When this desired normal operating pressure has been reached the needle-valve 27 will be slowly opened to permit the vapors to pass to the condenser 16, where they are condensed, the 55 condensed distillate draining into the receiving-drum 18.

We find that the quality of the distillate 60 collected in the reservoir 18 is dependent to an extraordinary degree upon the regularity with which the distillation process is conducted, small variations in the temperature and pressure and rate of evolution 65 of vapors within the still causing wholly disproportionate variations in the character

of the distillate collected. In view of this fact we find it of the utmost practical importance to control the operation of the distillation apparatus with the greatest degree of accuracy. The desired results are obtained by the apparatus illustrated through the manual operation of the needle-valve 27 controlling the discharge of vapors from the upper end of the air-condenser, and by the automatic operation of the stoker-control mechanism through which the firing of the furnace is regulated. By means of the conduit 31 the pressure of the vapors within the still is exerted upon the lower face of the diaphragm 33, and the balance-beam 36 70 having been appropriately loaded or weighted, any variation in the vapor pressure within the still will be effected to operate the piston-valve 39 and through the latter to control the movement of the piston 46. For 75 instance, if the pressure within the still drops below the predetermined operating pressure the balance-beam 36 is permitted to fall, thereby admitting fluid under pressure to the cylinder 41 and elevating the piston 46 therein. Through the connections 80 illustrated the throttle-valve of the stoker-engine 50 is thereby opened, permitting the engine to accelerate and to drive the stoker 11 at a faster rate, whereby the supply of 85 fuel to the furnace is increased. Simultaneously the damper 52 will be opened to supply the increased amount of air required for the higher rate of combustion. This more energetic firing of the furnace 10 will 90 continue until the increased evolution of vapors within the still has raised the pressure therein to the predetermined point, and, upon this pressure being attained the stoker-engine 95 will be automatically slowed down and the damper returned to the normal position. Conversely, any increase in pressure within the still will operate through the connections described to decrease the speed 100 of the stoker and correspondingly restrict 105 the supply of air to the furnace grates.

By the proper manipulation of the needle-valve 27, and through the automatic control of the firing of the furnace, we find it possible to accurately regulate the progress of 110 the distillation, conversion, and separation taking place within the still 12 and the connected inclined vapor conduit 13 and radiator 14. These latter elements are so designed and proportioned as to condense from 115 the outgoing stream of vapors and to constantly return to the still for further treatment therein those constituents of the mixture of hydrocarbon vapors which is evolved in the still which have not undergone sufficient decomposition, while permitting all of those constituents which have been sufficiently converted to pass without condensation. Inasmuch as the reflux fractionating 120 condenser, made up of the elements 13 and 125 140

14 is capable of effecting an accurate and complete separation between the vapors which have been sufficiently decomposed and those which have not been sufficiently 5 decomposed only when the rate of flow of the vapor current past the condensing surfaces closely approaches the normal or predetermined rate of flow for which the condenser was designed, it will be understood 10 that in view of this consideration alone the utmost accuracy of regulation of the process of distillation is required. This requirement of accuracy or regularity of action will be better understood when it is stated that approximately 15 seventy-five per cent. of the vapors passing from the still must be constantly condensed and returned to the still by the reflux fractionating condenser, only about twenty-five per cent. of such vapors, 20 passing the valve 25. It is therefore apparent that if the rate of distillation should be so increased as to permit only 2½% more vapors to pass through the conduit 13 and radiator 14 than the latter elements are capable of fractionating, such 2½% of insufficiently decomposed material would form an additional 10% of the distillate collected in the tank 18. So also, if the pressure is permitted to rise slightly, the resultant decreased 25 rate of evolution of vapors (assuming that the firing remains the same) will cause a considerable proportion of the sufficiently decomposed vapors which should pass through the condenser to be condensed therein. These desirable constituents, being returned to the still, suffer further change by which they are either cracked into 30 condensable gas or otherwise detrimentally affected. For these physical reasons only, therefore, and without regard to the serious 35 results from a chemical standpoint which are entailed by relatively minute or inconsiderable variations in the distillation and conversion process, it is important for the success of the process that every phase of it be under accurate control.

The pressure within the still system being relieved at the valve 25, the final condensation of the converted distillate is effected at atmospheric pressure only. A certain proportion of the vapors produced within the still are of such a character that they fail to condense under these conditions, and such vapors collect in the space above the liquid in the receiving-drum 18. From this drum they are led through the pipe 20 into the bottom of the Gay-Lussac tower 21 to pass upwardly through the interstices of the material within the tower. In their upward progress they meet a downwardly flowing current of a suitable absorbing menstruum such, for instance, as a finished or refined naphtha, the specific gravity of which it is desired to lower. By reason of 60 65 the intimate contact between the gas and

the liquid thus afforded a considerable proportion of the gas becomes absorbed in the liquid, enriching the latter and lowering its specific gravity. The incondensable gas which has failed of absorption escapes 70 through the pipe 22 and may be led to a gasometer or directly to a furnace to be used as gaseous fuel. The enriched naphtha is withdrawn from the bottom of the tower through the pipe 24.

While we have shown and described in considerable detail one specific form of apparatus for carrying out our invention, together with the exact procedure to be followed in the use of this apparatus in the treatment of a given class of raw materials for obtaining a particular product, it is to be understood that the foregoing is by way of illustration only and for the purpose of making the nature and objects of the invention more clear and that the invention is not to be regarded as limited to the illustrative process described except in so far as such limitations are included within the terms of the accompanying claims, in which it is our intention to claim all novelty inherent in our invention as broadly as is permissible in view of the prior art.

What we claim as new and desire to secure by Letters Patent, is:—

1. The process of distilling relatively heavy petroleum oils to obtain therefrom relatively light oils which consists in subjecting a liquid body of such heavy oil to distillation, leading off the evolved vapors through a reflux fractionating condenser in free communication with the still, restricting the outlet from the said condenser to maintain a pressure of upward of 4 atmospheres in the same and in the still to which it is connected, causing said condenser to continuously condense from the mixture of vapors therein substantially all insufficiently decomposed products without condensing any substantial proportion of sufficiently decomposed products, by controlling such restricted outlet, and condensing and collecting the sufficiently decomposed vapors which pass the said restricted outlet.

2. The process of distilling relatively heavy petroleum oils to obtain therefrom relatively light oils which consists in subjecting a liquid body of such heavy oil to distillation, leading off the evolved vapors through a reflux fractionating condenser in free communication with the still, restricting the outlet from the said condenser to maintain a pressure of upward of 4 atmospheres in the same and in the still to which it is connected, causing said condenser to continuously condense from the mixture of vapors therein substantially all insufficiently decomposed products without condensing any substantial proportion of sufficiently decomposed products, by controlling such re-

stricted outlet, passing the vapors escaping from the said outlet through a condenser, collecting the condensate, and subjecting the uncondensed vapors to the action of extensive surfaces of an absorbing menstruum.

3. The process of distilling relatively heavy petroleum oils to obtain therefrom relatively light oils which consists in subjecting a liquid body of such heavy oil to 10 distillation, leading off the evolved vapors through a reflux fractionating condenser in free communication with the still, restricting the outlet from the said condenser to maintain a pressure of upward of 4 atmos-

pheres in the same and in the still to which it is connected, causing said condenser to continuously condense from the mixture of vapors therein substantially all insufficiently decomposed products without condensing any substantial proportion of sufficiently decomposed products, by controlling such restricted outlet, condensing and collecting the sufficiently decomposed vapors which pass the said restricted outlet, and automatically controlling the heating of the still by 20 the vapor pressure therein.

ROBERT E. HUMPHREYS.
WILLIAM M. BURTON.
